US00D355562S

United States Patent [19]**DeFelip****Patent Number: Des. 355,562****Date of Patent: ** Feb. 21, 1995**

[54] **HOUSEHOLD ESPRESSO COFFEE MAKER MACHINE**

4,644,856 2/1987 Borgmann ..... D7/309 X
4,852,474 8/1989 Mahlich et al. ..... D7/309 X

[75] Inventor: **Aldo DeFelip, Milano, Italy**

Primary Examiner—Alan P. Douglas

[73] Assignee: **Gaggia S.r.l., Modena, Italy**

Assistant Examiner—M. N. Pandozzi

[**] Term: **14 Years**

Attorney, Agent, or Firm—Sughrue, Mion, Zinn,
Macpeak & Seas

[21] Appl. No.: **12,258**

CLAIM

[22] Filed: **Aug. 27, 1993**

The ornamental design for a household espresso coffee
maker machine, as shown and described.

[30] **Foreign Application Priority Data**

Apr. 27, 1993 [XH] Hague Agreement DMA/002135
[52] U.S. Cl. **D7/309; D7/310;**

D7/311

[58] **Field of Search** **D7/300, 305, 309, 310,**
D7/311, 312; 99/295, 300, 304, 307, 306

DESCRIPTION
